UNITED STATES PATENT OFFICE.

ALEXANDER CAMERON, JR., OF RICHMOND, VIRGINIA.

DESIGN FOR A COVER FOR BOXES OR CANS.

SPECIFICATION forming part of Design No. 28,405, dated March 22, 1898.

Application filed May 13, 1897. Serial No. 636,398. Term of patent 14 years.

to all whom it may concern:

Be it known that I, ALEXANDER CAMERON, a citizen of the United States, residing at Richmond, in the county of Henrico and State of Virginia, have invented and produced a new and original Design for a Cover for Boxes or Cans; and I do hereby declare the following to be a full, clear, and exact description of the same, reference being had to the accompanying drawing, forming a part thereof.

In the accompanying drawing the figure is a perspective view of a cover for a box or can embodying my design.

The leading feature of my design consists of a cylindrical-shaped cover for a box or can formed with diagonally-arranged spaced grooves projecting outwardly from the vertical flange of the cover, and a peripheral groove formed in the upper inner circumferential edge of the cover.

A represents the body of the cover, which

is cylindrical in shape, and which is shaped to form diagonally-arranged grooves a , projecting outwardly from the vertical flange of the cover and extending down to the lower edge of the cover, as at a' a'' , so that the lower edge of the cover will appear slightly projecting at these points. On the inside of the cover at the upper edge of the vertical flange thereof appears a peripheral groove or recess a^2 .

Having now described my design, what I claim as new, and desire to secure by Letters Patent, is—

The design for a cover for a box or can, substantially as herein shown and described.

In testimony whereof I hereunto affix my signature in presence of two witnesses.

ALEXANDER CAMERON, JR.
